COIL ANNEALING FURNACE

James C. Woodson, Cleveland, Ohio, assignor to
 Lee Wilson Sales Corporation, Cleveland, Ohio,
 a corporation of Ohio

Application September 2, 1937, Serial No. 162,132

3 Claims. (Cl. 266—5)

This invention relates to a furnace for the heat treatment of material in coils, particularly to the annealing of steel or other metallic strip.

In one type of coil annealing furnace which 5 has been proposed heretofore, a base on which the coil was disposed for heat treatment was adapted to receive an inner protective cover having an out-turned horizontal flange adjacent its bottom, and a heating cover adapted to rest on said flange. The lower portion of the inner cover of such furnace is thus firmly held circumferentially and expansion and contraction due to heating and cooling of the furnace cause a considerable degree of warping of the inner cover.

15 I have invented a novel coil annealing furnace which overcomes the aforementioned objection to the device of the prior art described above and is characterized by additional features of novelty and utility. In accordance with my invention I provide a base adapted to receive a coil or a plurality of coils. A sealing channel extends around the base at a level below the latter, providing a seat for the lower edge of an inner protective cover. A heating cover is adapted to be disposed over the protective cover and the base. I provide a support for the heating cover independent of the base on which the coils are supported. The heating cover has an inward flange adjacent its bottom extending toward the base, but clearance is provided between the base and the flange, and the lower portion of the protective cover extends through this annular space. The inner cover is free to expand and contract without binding, thus preventing warping or 35 other injury to the cover.

For a complete understanding of the invention, reference is made to the accompanying drawing, illustrating a present preferred embodiment, and to the following detailed description which is to be read in connection therewith.

40 In the drawing:

The single figure is a vertical transverse section through a coil annealing furnace according to my invention.

45 Certain features of the furnace are repeated about the circumference thereof, but showings of such elements are omitted for the sake of clearness.

Referring now in detail to the drawing, a furnace indicated generally by the numeral 10 comprises a base or hearth 11 and a heating cover 12 adapted to be lowered thereover. The hearth 11 is composed of refractory brick laid on a bottom sheet 13, supported by columns 14, and web 55 plates 15, spaced circumferentially of the base

and carried on radially disposed beams 16 which rest on a suitable foundation 17. A conical skirt 18 depends from the plate 13. The skirt 18, together with an annular bottom ring 19, and a peripheral outer side wall 20 defines a sealing channel 21 extending around the base but positioned below the latter.

5 A coil supporting casting 22 is disposed on the refractory portion of the hearth and has a circular opening 23 therein. Coils are disposed on 10 the casting 22, as indicated at 24. A circulating fan 25 is journaled in bearings embedded in the refractory portion of the base or supported therefrom on a ring 26. A motor 27 is also carried on the ring and is directly connected to the fan. 15

A protective cover 28 has a circumferentially cylindrical upper side wall and dished top 29. The lower portion of the side wall of the cover flares outwardly as at 30, to conform with the frusto-conical shape of the refractory portion of 20 the base. The downwardly flaring portion 30 of the cover terminates in a cylindrical lower edge 31 adapted to seat in the sealing channel 21.

The heating cover 12 comprises a refractory side wall and roof assembled within a structural frame including members 32 and sheet metal panels 33. Heat exchange tubes 34 are spaced circumferentially about the side wall of the heating cover, each tube having a burner 35 in its lower end. The burners 35 are connected to a 30 fuel supply header 36, and igniter electrodes 37 are mounted adjacent each burner for initiating combustion of fuel issuing therefrom.

A flange 38 of refractory material extends inwardly from the lower edge of the cover 12, toward the base 11. The cover is provided with a bottom ring 39 adapted to seat on an annular support composed of a channel 40 bent to circular form resting on circumferentially spaced columns 41. The columns 41 extend upwardly 40 from the foundation 17. The latter constitutes a common footing for the columns 41 and beams 16, but the structures carried thereon for supporting the cover 12 and base 11, respectively, are, nevertheless, independent of each other. 45

In describing the manner of using the structure explained above, it will be assumed that the heating cover 12 and the protective cover 28 have both been removed from the positions in which they are shown, and a coil such as that shown 50 at 24 is disposed on the supporting casting 22. It will be understood that a plurality of coils of relatively narrow strip may be so positioned on the casting as to occupy the same space as the single coil 23 of relatively wide strip. The pro- 55

5 tective cover 28 is then replaced and finally the heating cover 12, the covers being most conveniently handled by means of an overhead crane. Fuel is then delivered to the burners 35 and ignited by sparks from the electrodes 37. The fan 25 is driven during the heating portion of the cycle to accelerate absorption of the heat by the coil through the protective cover. Any desired type of inert or non-oxidizing atmosphere may 10 be supplied within the protective cover 28, by known means. It will be apparent that the space defined by the bottom plate 13, the skirt 18 and the protective cover 28 may be made entirely gas tight, the sealing material in the channel, 15 which may be either liquid or granular, effectively sealing the space between the lower edge of the cover and the skirt 18. Since the channel 21 is outside the furnace, liquid sealing material, such as oil, may be employed. When the 20 coil 24 has been heated to the desired temperature, the heating cover 12 is removed and deposited over a fresh coil resting on another base similar to that shown at 11 and enclosed within its own protective cover. The coil 24 is permitted 25 to cool slowly in the atmosphere provided within the cover 28, the latter protecting the coil against contact with the atmosphere.

As will be apparent from the drawing, the lower portion of the protective cover extends through 30 an annular clearance space between the base 11 and the inward bottom flange 38 of the heating cover 12. The latter does not rest on the base but on the supporting ring 40 which is spaced outwardly from the base. The cover 28 has full opportunity of expanding and contracting freely as 35 a result of the different temperatures which exist in various portions thereof, without binding, warping, or other injurious effects.

Although I have illustrated and described 40 herein but one preferred form of the invention it will be understood that changes in the construction described may be made without departing from the spirit of the invention or the scope of the appended claims. As an example of such 45 changes, the base and covers could be made

square or rectangular in plan instead of the preferred cylindrical form shown in the drawing.

I claim:

1. A furnace comprising a charge-supporting base having a refractory layer thereon and a 5 heating cover having a refractory lining therein, said cover being adapted to be lowered over said base, the portions of said layer and lining which are adjacent when the cover is in cooperative position over said base being shaped and 10 dimensioned to provide a frusto-conical clearance space therebetween, a sealing channel extending around said base and spaced radially outward of the margin of said layer, and a protective cover adapted to be disposed over said 15 base before the heating cover is lowered thereover, said protective cover having a portion adjacent its bottom edge shaped to fit in said space when said edge is seated in said channel.

2. A furnace comprising a base adapted to support a charge, a sealing channel below said base and extending therearound, a protective cover adapted to be disposed over the charge with its lower edge in said channel, and a heating cover adapted to be lowered over said protective cover, 25 said heating cover having an inwardly projecting bottom flange approaching said base, the adjacent surfaces of said base and flange being frusto-conical and providing a similarly shaped annular space therebetween, the wall of said protective cover extending through said space.

3. In a furnace, a base adapted to support a charge, a portable heating cover adapted to be lowered over said base, a foundation, a series of columns extending upwardly therefrom for supporting said cover, a second series of columns spaced outwardly from the first series for supporting the base on said foundation, a sealing channel between said series of columns, and a protective cover adapted to overlie a charge on said 40 base and extending downwardly below said base through an annular space between it and said heating cover into said channel.

JAMES C. WOODSON.
